US0D1072743S

(12) **United States Design Patent** (10) **Patent No.:** **US D1,072,743 S**
(45) **Date of Patent:** **** Apr. 29, 2025**

(54) **WIRELESS CHARGER**

(71) Applicant: **Guangdong Aoyun Technology Co., Ltd.**, Guangdong (CN)

(72) Inventor: **Xueping Zhu**, Guangdong (CN)

(73) Assignee: **Guangdong Aoyun Technology Co., Ltd.**, Guangdong (CN)

(**) Term: **15 Years**

(21) Appl. No.: **29/980,157**

(22) Filed: **Dec. 23, 2024**

(30) **Foreign Application Priority Data**

Dec. 16, 2024 (CN) 202430796396.X

(57) **CLAIM**

The ornamental design for a wireless charger as shown and described.

DESCRIPTION

FIG. 1 is a front, left and top perspective view of a wireless charger, showing my new design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The dashed broken lines depict portions of the wireless charger that form no part of the claimed design.

1 Claim, 8 Drawing Sheets
